UNITED STATES PATENT OFFICE.

HAGOP P. TEVONIAN, OF BROOKLYN, NEW YORK

PENCIL SHARPENER.

Application filed June 9, 1927. Serial No. 197,624.

This invention relates to a pencil sharpener of the type used by draftsmen and others to place an extra fine point on the lead of a pencil.

5 It is common practice to sharpen the point by rubbing it over a piece of fine sandpaper kept on the desk for this purpose. This is an inconvenient and messy operation and results in graphite dust soiling the fingers and getting blown about the desk.

10 The present invention avoids these difficulties by providing a receptacle that is normally closed in a dust-proof manner and has a hinged side carrying an abrasive on its inner surface. The parts are so arranged that the abrasive surface is readily accessible for sharpening the lead when the side is turned down, and upon closing the side the graphite dust is trapped in the receptacle.

15 While a preferred form of the invention has been disclosed for purposes of illustration, it should be understood that various changes may be made in the structure without departing from the spirit and scope of the invention as hereinafter set forth and claimed.

20 Fig. 1 is a plan view of the pencil sharpener.

25 Fig. 2 is a section on line 2—2 of Fig. 1. Fig. 3 is a view similar to Fig. 2 with the parts in open sharpening position.

30 Fig. 4 is a perspective view of the sharpener in operating position.

35 Referring to the drawings more specifically, the base 10 is formed at one end with a handle portion 11 and is apertured at 12 to permit hanging the sharpener on a nail if found convenient.

40 A box-like receptacle is formed by a rear wall 13 and sloping end walls 14, the front side being without a rigid wall. The walls 13 and 14 are grooved near their upper ends as at 15 to receive the removable transparent plate 16, which is inserted into the grooves from the open side of the receptacle.

45 A shaft 17 extends through the end walls 14 just above the base 10 and on its end toward handle 11 carries an operating crank 18. A plate 19 is non-rotatively mounted on shaft 17 and is of such a size that it completely closes the open side of the receptacle when the parts are in the closed position of Fig. 2. Any suitable abrasive surface, such as a fine steel file 20, is secured to the inner side of plate 19, and felt pads 21 for

cleaning the end of the lead after it has been sharpened are also carried on the inner side of the hinged plate.

50 A felt insulator 22 has its lower edge fastened to the base 10, and its upper edge projects above the top of plate 19 and contacts with the top plate 16 to maintain a dust-proof closure. In order to maintain the box in closed position, a spring 23 is arranged 55 with its lower end fastened to the base and its upper end engaging the plate 19 to normally bias the hinged side to the position of Fig. 2.

55 In order to use the sharpener the crank 18 is pressed downwardly until the hinged side is in the position of Fig. 3, in which position the abrasive surface is exposed for use as shown in Fig. 4. After sharpening the lead and cleaning it on one of the pads 70 21, the pencil is removed and the handle released, permitting the spring 23 to close the hinged side and throw the graphite dust from the file into the closed receptacle. The transparent top plate 16 permits visual 75 inspection of the sharpening process, and can be slid from the grooves 15 when it is desired to empty the accumulated dust from the receptacle.

I claim:

80 1. A pencil sharpener comprising a receptacle having a top and a hinged side, hinged substantially central of the base and having its free edge engaging said top, the inner face of the hinged side being provided with an abrasive surface.

85 2. A pencil sharpener comprising a receptacle having a top, a hinged side hinged substantially central of the base and having its free edge engaging said top, the inner 90 face of the hinged side being provided with an abrasive surface, and a spring normally biasing the hinged side to closed position.

95 3. A pencil sharpener comprising a receptacle having a top, a hinged side, the inner 100 face of the hinged side being provided with an abrasive surface, a spring normally biasing the hinged side to closed position, and an operating handle for opening the hinged side.

105 4. A pencil sharpener comprising a receptacle having a transparent top and a hinged side hinged substantially central of the base and having its free edge engaging said top, the inner face of the hinged side 110 being provided with an abrasive surface.

5. A pencil sharpener comprising a re-

ceptacle having a transparent top, a hinged side hinged substantially central of the base and having its free edge engaging said top, the inner face of the hinged side being provided with an abrasive surface, and a spring normally biasing the hinged side to closed position.

6. A pencil sharpener comprising a receptacle having a transparent top, a hinged side, hinged substantially central of the base and having its free edge engaging said top, the inner face of the hinged side being provided with an abrasive surface, a spring normally biasing the hinged side to closed position, and an operating handle for opening the hinged side.

7. A pencil sharpener comprising a receptacle comprising three closed sides, grooves in the sides, a transparent top plate removably fitting in the grooves, a rotatable shaft extending through the receptacle near its bottom and carrying an operating handle

outside the receptacle, a pivoted side plate non-rotatably secured to shaft, and having its inner face provided with an abrasive surface and a spring normally biasing the pivoted side to closed position.

8. A pencil sharpener comprising a receptacle comprising three closed sides, grooves in the sides, a transparent top plate removably fitting in the grooves, a rotatable shaft extending through the receptacle near its bottom and carrying an operating handle outside the receptacle, a pivoted side plate non-rotatably secured to the shaft, the inner face of the pivoted side being provided with an abrasive surface and a felt cleaning pad, a felt insulator on the outside of the pivoted side and engaging the top and bottom walls of the receptacle to form a dust-proof closure, and a spring normally biasing the pivoted side to closed position.

In testimony whereof I affix my signature.
HAGOP P. TEVONIAN.
